[57] CLAIM

The ornamental design for a combined door bumper
and patch for damaged walls, as shown and described.

DESCRIPTION

FIG. 1 is a perspective view of a combined door bumper
and patch for damaged walls according to the design;

FIG. 2 is an enlarged top plan view of a combined door
bumper and patch for damaged walls according to the
design, the bottom being a mirror image;

FIG. 3 is an enlarged front elevational view of a com-
bined door bumper and patch for damaged walls ac-
cording to the design, the rear being plain and unor-
namented; and,

FIG. 4 is an enlarged right side elevational view of a
combined door bumper and patch for damaged walls
according to the design, the left side being a mirror
image.

FIG.1

FIG.2
